WITNESS.

UNITED STATES PATENT OFFICE.

LOUIS E. PORTER, OF CONNELLSVILLE, PENNSYLVANIA.

MOISTENER.

Application filed January 14, 1922. Serial No. 529,249.

To all whom it may concern:

Be it known that I, LOUIS E. PORTER, a citizen of the United States, residing at Connellsburg, in the county of Fayette and State 5 of Pennsylvania, have invented new and useful Improvements in Moisteners, of which the following is a specification.

My present invention has reference to an envelope moistener.

10 My object is to produce an article of this character which can be readily secured on the back of the hand of the operator to permit of the free use of his hands and the ready passage of the capilliform element of 15 the improvement over the glued surface of an envelope.

It is a further object to produce an envelope moistener comprising a hollow water receptacle whose under face is shaped to 20 conform to the outer contour of a human hand on which the device is clasped, means being provided upon the said face of the body to engage between the fingers of the operator to hold the body against lateral 25 movement, and said body having its outer face convex and provided with a capilliform element which projects both inwardly and outwardly therefrom whereby the outer face of the said element may be wiped over the 30 gummed surface of an envelope in an accurate and expeditious manner without inconvenience to the operator.

The foregoing, and other objects which will appear as the nature of the invention is 35 better understood, may be accomplished by a construction, combination and operative association of parts, such as is disclosed by the drawings which accompany and which form part of this specification.

40 In the drawings:—

Figure 1 is a view illustrating the application of the improvement.

Figure 3 is a substantially central vertical longitudinal sectional view through the 45 improvement.

Figure 3 is a bottom plan view thereof.

Figure 4 is a sectional view through a modification.

As disclosed in Figure 1 of the drawings my improvement is designed to be arranged on the back of the hand of the operator, directly over his fingers, but is in a position which will not interfere with the free movement of the fingers.

55 The improvement is comparatively small,

light in weight, and is of a form, as will presently be apparent, to snugly accommodate itself to the hand of the operator.

The improvement includes a body in the nature of a water receptacle 1. This body 60 has its under face concaved, as at 2, and its outer face convex, as at 3. The concaved under face 2 of the body is provided with a depending rib 4 which is designed to be received between the fingers of the operator 65 and thereby hold the device against lateral movement when positioned. The sides of the body are preferably rounded and are provided with comparatively small U-shaped members or bails 5 to which are connected 70 the ends of an elastic band 6. If desired, the band may comprise two sections, one of which having a buckle and the other having apertures to receive the tongue of the buckle. In any event, the band is arranged around 75 the hand of the operator for clamping the body 1 thereon.

The body 1, as previously stated, is designed to contain water, and the same on its outer convex face is preferably centrally 80 formed with a threaded opening 6 in which is screwed a sleeve 7 that has passed therethrough a wick or other capillary agent 8. The wick may be readily adjusted with respect to the sleeve, and it will be apparent 85 that by simply turning over his hand, the operator may cause the wick to be passed over the glued surface of an envelope to be moistened.

In Figure 4 of the drawings, the body 9 90 is similar to that previously described, being provided with the attaching strap or band. The convex or arched top of the body is, however, in this instance provided with a laterally extending slot through which is passed 95 a wick or capillary agent of a length corresponding to that of the slot. The body 9 is also provided with a normally closed filler opening, indicated by the dotted lines in the said figure, and indicated by the numeral 11.

100 It is thought that the foregoing description, when taken in connection with the drawings will fully set forth the construction, operation and advantages of the improvement, and that further detailed description will not be required. It is thought necessary to state, however, that I am not to be restricted, in the manufacturing and marketing of my improvement to the pre- 110

cise details of construction herein set forth, but am entitled to all such changes therefrom as fall within the scope of what I claim.

Having described the invention, I claim:—

- 5 1. An envelope moistener designed to be clamped on the back of the hand of an operator, comprising a water containing body whose under face is concaved and whose outer face is convex, a rib on the under face of the body designed to be received between the fingers of the operator, and a capillary agent in the body and projecting through the outer face thereof.
- 10 2. In an envelope moistener which is de-

signed to be clamped on the back of the 15 hand of an operator, a hollow water containing body whose under face is concaved and whose outer face is convex, said body having its under face provided with a rib designed to be received between the fingers of 20 the operator, bails on the ends of the body, a strap secured to the bails and arranged around the hand of the operator, and a capillary agent received in the body and projecting through the outer convex face 25 thereof.

In testimony whereof I affix my signature.

LOUIS E. PORTER.
